STETHOSCOPE CHEST PIECE

Noa Spears, Jr., San Antonio, Tex.

Application September 8, 1958, Serial No. 52,548

Term of patent 14 years

(Cl. D83—12)

Fig. 1 is a side elevational view of a stethoscope chest piece embodying my new design;

Fig. 2 is a top plan view thereof;

Fig. 3 is a right end elevational view thereof; and

Fig. 4 is a bottom perspective view thereof showing the right end and the side opposite that shown in Fig. 1.

I claim:

The ornamental design for a stethoscope chest piece, substantially as shown.
